UNITED STATES PATENT OFFICE.

FRANK A. SCHUETZ, OF CHICAGO, ILLINOIS, ASSIGNOR TO THE ADAMS & WESTLAKE COMPANY, A CORPORATION OF ILLINOIS.

LAMP-BURNER.

No. 833,004.

Specification of Letters Patent.

Patented Oct. 9, 1906.

Application filed April 30, 1906. Serial No. 314,475.

To all whom it may concern:

Be it known that I, FRANK A. SCHUETZ, a citizen of the United States, and a resident of Chicago, county of Cook, and State of Illinois, have invented certain new and useful Improvements in Lamp-Burners, of which the following is a specification, and which are illustrated in the accompanying drawings, forming a part thereof.

The invention relates to burners for that type of lamp used for signaling purposes by railroads and commonly known as the "long-time" burner, the lamp being expected to burn for several days without trimming or refilling.

The object of the invention is to provide a burner of this type capable of giving a strong flame and so guarding the flame that the danger of its extinguishment by air-currents is greatly reduced.

The invention consists in the structure hereinafter described, and which is illustrated in the accompanying drawings, in which—

Figure 1 is a plan view of the burner. Figs. 2 and 3 are vertical sections on the lines 2 2 and 3 3, respectively, of Fig. 1; and Fig. 4 is a plan view of a detail of the construction separated from other parts.

The burner comprises a body portion 10, having a threaded neck for engagement with the lamp-body, and a wick-tube 11, passing through and extending above the body, suitable fingers 12 being provided for supporting and clamping a chimney. (Not shown.) A plate 13 is secured to the upper end of the wick-tube and extends laterally therefrom. This plate is apertured upon diametrically opposite sides of the wick-tube, as shown at 14 15, and from the inner edges of these apertures there rise flaring wings 16 17. Intermediate of the apertures 14 15 the plate is apertured, as shown at 18 19, and from the outer margins of these apertures rise a pair

of inwardly-inclined lips 20 21. As thus far 45 described, the burner is similar to the burner forming the subject of my application for Letters Patent Serial No. 296,164.

From the outer edges of the plate 13 depends an annular skirt 22, which terminates 50 above the top of the body 10 and serves to steady the flame by directing all of the air-currents upwardly, so that no cross-currents or angular currents reach the flame, except such as are deflected upon it by the lips 20 55 and 21. The skirt 22 gathers within itself a solid column of air, which passes upwardly through the apertures in the plate 13. The air passing through the ports 18 19 is inclined inwardly and supplies the necessary 60 oxygen for developing a strong flame. The air passing up through the ports 14 15 provides a supplemental supply which combines with the carbon at the margins of the flame, and thus prevents the development of smoke. 65 These columns also sweep the inner surface of the chimney and protect it from smut.

I claim as my invention—

1. In a burner, in combination, a wick-tube, flaring wings rising from opposite sides 70 of the end of the tube, ported plates extending laterally from the end of the tube and intermediate of the wings, and an annular skirt depending from the plates and being open at the bottom.

2. In a burner, in combination, a wick-tube, a plate extending laterally from the tube end and downwardly flanged at its outer edge, and apertured through its upper face to form tongues, one pair of such tongues 80 being oppositely disposed and inclined upwardly and outwardly, and one pair thereof being oppositely disposed and inclined upwardly and inwardly.

FRANK A. SCHUETZ.
